To all whom it may concern:

Be it known that I, JOHN TERHUNE, a citizen of the United States, residing at Chicago, Illinois, have invented and produced a new and 5 original Design for the Ornamentation of Book-Covers, of which the following is a specification.

My design is an ornamentation for covers of albums and other books. Its leading features 10 are the representation of army-badges in the upper right-hand corner, a flag in the upper left-hand corner, and the figure of a star or medallion in the center with the head of a man represented therein, and the name of the book 15 preferably in the lower right-hand corner. The points of the star, where a star is used, may contain representations of army and naval implements—as swords, anchors, guns, cannons, and the like—and these implements may also be represented in other portions of the 20 figure. The flag may be of red, white, and blue, gilt, bronze, or black, or any other color, and the other features such colors as may be desired.

I claim—
